ELECTRICAL COMMUNICATION SYSTEM

Prafulla Kumar Chatterjea and Dermot Min Ambrose, London, England, assignors, by mesne assignments, to International Standard Electric Corporation, New York, N. Y., a corporation of Delaware.

Application February 16, 1943; Serial No. 476,072
In Great Britain March 13, 1942

10 Claims. (Cl. 250—6)

1

The present invention relates to electrical communication systems and according thereto provides a transmission system in which the bandwidth of the transmitted frequencies is modulated in accordance with the amplitude of the intelligence or signal wave to be communicated. The resulting waveform may be transmitted along a line or may be used to modulate a carrier wave in known manner. The modulated carrier may be transmitted in any known manner, for example, radio, cable or dielectric guides.

In one system according to the present invention an amplitude modulation in accordance with the intelligence or signal wave to be communicated is set up in the harmonics of a distorted sine wave whilst the amplitude of the fundamental frequency of the said distorted sine wave is maintained constant.

In one embodiment of the invention a sine wave whose frequency is higher than the highest modulation frequency component of the intelligence wave to be transmitted is amplitude modulated in accordance with the signal or intelligence wave by any known method. This modulated waveform is then passed through a limiter circuit in such a way as to limit the amplitude of the modulated wave to at least that of the smallest amplitude sine wave produced in the modulation. The resulting waveform may thus vary from a sine wave in one case to a 50% pulse with a certain harmonic content, that is, the number of harmonics of the fundamental frequency of the sine wave, depending on the modulation depth. This waveform is used to modulate a carrier wave and since this modulation varies in amplitude between two fixed values, namely zero and the amplitude of the fundamental sine wave, the carrier can be modulated to 100% without risk of over modulating.

In one suitable form of receiving arrangement the modulated carrier is received on a receiver which is capable of handling the necessary bandwidth and the detected wave is limited in amplitude for noise reduction and passed through a high pass filter. This filter is so designed that the fundamental frequency of the detected wave is greatly attenuated while the harmonics are allowed to pass freely. These harmonics may be each looked upon as a carrier (harmonic carriers) modulated in amplitude by the original signal or intelligence wave. The output of the filter is passed through a rectifier and then through a low pass filter which attenuates the "harmonic carrier" frequencies but passes the intelligence frequencies. These latter are ampli-

fied as necessary and passed to the work or translating device.

The invention will be more fully described with reference to the accompanying drawings in which:

Fig. 1 is a schematic diagram of a transmitter for carrying out the invention;

Fig. 2 shows the waveform at point 11 of Fig. 1;

Fig. 3 shows the waveform at point 13 of Fig. 1;

Fig. 4 shows the waveform at point 15 of Fig. 1;

Fig. 5 is the schematic diagram of receiving arrangements for co-operation with a transmitter as in Fig. 1 or any other modulated frequency band transmitter.

In Fig. 1 the signal voltage wave representing the intelligence to be transmitted is fed across 1 and 2 to the control grid of valve V₁ while a sine wave of a frequency in excess of the highest modulation frequency of the intelligence wave is fed across 3 and 4 to the control grid of valve V₂. Resistance 17 is an anode load which is common to valves V₁ and V₂ and thus across resistance 17 will be developed the sine wave from points 3 and 4 and this will be amplitude modulated in accordance with the waveform imposed on the grid of V₁ from points 1 and 2. This modulated sine wave is shown in Fig. 2, the hatched portion showing the limits of modulation.

The output from valves V₁ and V₂ is fed into a limiting circuit one form of which may consist of diodes V₃ and V₄ and their associated network of resistances and condensers as shown in Fig. 1. Positive volts which may be varied by resistance 19 are applied to the cathode of V₃ and are adjusted in such a manner that the diode V₃ and condenser 21 pass all positive voltages applied to its anode in excess of the preset voltage on the cathode. Thus the positive part of the waveform in Fig. 2 between the lines 23 and 25 is removed. Similarly by applying the waveform to the cathode of the diode V₄ and adjusting the positive volts on its anode by resistance 31 a negative part of the waveform in Fig. 2 is bypassed through V₄ and condenser 33. This part which is removed is shown between the lines 27 and 29 in Fig. 2. The resulting waveform is shown in Fig. 3 and it will be observed that the slope of the waveform or pulse depends upon the amplitude of the modulating wave and the component harmonic frequencies or bandwidth of the waveform or pulse depends upon the slope of the leading and trailing edges of the waveform. This waveform may now be used to modulate a carrier wave in any known manner. The envelope of

3

the final modulated carrier waveform is shown in Fig. 4.

The circuit diagram of a receiving arrangement is shown in Fig. 5. The signal is primarily received by any known technique, care being taken that the circuits involved can handle the frequency bandwidths required which is limited by the modulation depth in the transmitter. The signal, from the detector of the radio receiver 35 at the points 7 and 8 which is shown in Fig. 3 is fed into a limiter circuit one type of which is shown consisting of V₅ and V₆, which are diodes, and their associated circuits. The principle of operation is exactly similar to the limiters in the transmitter (Fig. 1) and V₃ coincides with V₅; V₄ with V₆; resistances 19 and 31 (Fig. 1) with resistances 37 and 39 (Fig. 5) respectively; and condensers 21 and 33 (Fig. 1) with condensers 41 and 43 (Fig. 5) respectively. The purpose of this limiter is to reduce noise by limiting the noise components from the crests and troughs of the received pulses.

The output from the limiter V₅ and V₆ is now passed through condenser 45 to a high pass filter 47. This filter is so designed as regards its cut off frequency that it heavily attenuates the fundamental frequency of the pulse train applied to it while allowing free passage to the harmonics in the pulse. The wave-form at the output terminals 9 and 10 of the filter is thus a complex carrier composed of the harmonics contained in the pulse and which bear the initial intelligence voltage wave in the form of an amplitude modulation.

The output from the high pass filter 47 is fed through a diode V₇ on resistance 49 to perform the necessary detection of this "harmonic" carrier and thence via terminals 12 and 14 to a low pass filter 51. This latter is so arranged that the cut off frequency is at the same frequency or slightly lower than that of the fundamental frequency of the wave-form at points 7 and 8 in Fig. 5 and which is shown in Fig. 3. The output from this filter 51 at points 16 and 18 is the voltage corresponding to the intelligence or signal wave which is transmitted and may be connected to a speaker or some such appliance for audibility, or other work device.

Whereas the more conventional systems of radio transmission and reception are subject to noise interference, this system as described gives a greater signal noise ratio due to the limiting circuits in the receiver and also to the filters which allow only part of the noise spectrum to pass.

A greater modulation depth in the radio frequency carrier may be obtained than with amplitude modulation systems since the amplitude of the pulses is constant. There is also the greater peak power transmission for a given valve than is normally associated with forms of pulse transmission.

Whilst only one specific embodiment of the invention has been described, others falling within the scope of the appended claims will occur to those skilled in the art. For example, to obtain the intelligence signals from the received modulated band-width signals, a damped oscillatory circuit may be employed and the received detected signals applied to shock excite the oscillatory circuit. The amplitude of the initial cycle of the oscillation produced depends upon the rate of change of strength of the exciting current with time, and thus since the slope of the edges of the

4

detected received wave-form or pulses vary in accordance with the amplitude of the initial intelligence or signal wave, if the detected received wave-form or pulses be applied to shock excite the damped oscillatory circuit, preferably tuned to the pulse repetition frequency, or the frequency of the detected wave-form, the output of said circuit will follow the amplitude variations of the initial signal wave. The output of the oscillatory circuit may then be applied directly to a translating device or other work device.

What is claimed is:

1. In an electrical communication system, means for producing electrical intelligence waves of varying amplitudes, means for modulating less than 100% the amplitude of a sine wave whose frequency is higher than the highest modulation frequency component of the intelligence wave to be communicated, circuit means for limiting the amplitude of said modulated wave to at least that of the smallest amplitude sine wave produced in the modulation, and means for modulating a carrier wave in accordance with the wave-form produced by said circuit means.

2. In an electrical communication system, means for producing electrical intelligence waves of varying amplitudes, means for producing a wave-form varying from pure sine wave to a pulse with a predetermined harmonic content, and means for modulating said wave-form in accordance with said amplitudes, the number of harmonics of the fundamental frequency of said sine wave depending on the depth of the modulation.

3. In an electrical communication system, means for producing electrical intelligence waves of varying amplitudes, means for modulating less than 100% the amplitude of a sine wave whose frequency is higher than the highest modulation frequency component of the intelligence wave to be communicated, circuit means for limiting the amplitude of said modulated wave to at least that of the smallest amplitude sine wave produced in the modulation, means for modulating a carrier wave in accordance with the wave-form produced by said circuit means, whereby this modulation varies in amplitude between the two fixed values of zero and the amplitude of the fundamental sine wave.

4. An electrical communication system for transmitting and receiving intelligence comprising means for generating signal waves having a predetermined fundamental frequency, means for varying the time rate of change of said waves between two amplitude levels in accordance with the intelligence to be transmitted while maintaining the maximum amplitude and the fundamental frequency of said waves substantially constant, means for transmitting said distorted waves, means for receiving said distorted waves and means for demodulating said waves.

5. An electrical communication system for transmitting and receiving intelligence waves comprising means for generating signal waves having a predetermined frequency, means for varying the time rate of change of said waves between two fixed amplitude levels corresponding to the lowest amplitude intelligence waves, in accordance with the intelligence to be transmitted, means for generating a carrier wave, means for modulating said carrier waves by said distorted waves, means for transmitting said modulated carrier waves, means for receiving said modulated carrier waves, means for detecting said modulated carrier wave and means for demodu-

lating the output signals of said detecting means.

6. An electrical communication system for transmitting and receiving intelligence comprising a source of electrical waves whose amplitude vary with the intelligence being transmitted, a source of carrier frequency sine waves, means for amplitude modulating said carrier waves with said electrical waves to derive complex waves, means for varying the harmonic content of said complex waves in accordance with said amplitudes while leaving the fundamentals and amplitude of said complex waves unmodulated comprising means for varying the time rate of change of said complex waves to change between two amplitude levels in accordance with said amplitudes, means for transmitting the modulated complex waves, means for receiving said modulated complex waves, means for detecting said modulated complex waves, and means for attenuating the fundamental frequency of the detected wave while freely passing the harmonics, means for deriving said intelligence from said harmonics.

7. In a communication system a source of modulating waves, a source of carrier waves, means for amplitude modulating said carrier waves with said modulating waves to obtain modulated waves, means for limiting said modulated waves to the amplitude corresponding to the lowest amplitude modulating wave to derive waves harmonically related to the frequency of the lowest amplitude modulating waves and amplitude modulated in accordance with the modulating waves, and unmodulated waves at the frequency of the lowest amplitude modulating waves, and means for transmitting said derived and said unmodulated waves.

8. An arrangement according to claim 7, wherein said modulating waves comprise sine waves and said means for limiting comprises means for limiting the amplitude of the modulated waves to the amplitude of the lowest amplitude sine waves.

9. A receiving system for carrier waves amplitude modulated in accordance with a source of modulating waves, said modulated waves comprising waves harmonically related to the frequency of the lowest amplitude modulating waves and amplitude modulated in accordance with the modulating waves, and unmodulated waves at the frequency of the lowest amplitude modulating waves, comprising means for receiving said modulated carrier waves, a high pass filter, means for applying said received waves to said filter to attenuate the unmodulated waves while passing said waves harmonically related to the frequency

of the lowest amplitude modulating waves, means for amplitude detecting the passed harmonically related waves, a low pass filter, means for applying said amplitude detected waves to said low pass filter to derive said modulating waves.

10. An electrical communication system for transmitting and receiving intelligence comprising a source of modulating waves, a source of carrier frequency waves, means for amplitude modulating said carrier waves with said modulating waves to obtain modulated waves, means for limiting said modulated waves to the amplitude corresponding to the lowest amplitude modulating waves to derive waves harmonically related to the frequency of the lowest amplitude modulating waves and amplitude modulated in accordance with the modulating waves, and unmodulated waves at the frequency of the lowest amplitude modulating waves, means for transmitting said derived and unmodulated waves, means for receiving said transmitted waves, means for separating said unmodulated waves from said waves harmonically related to the frequency of the lowest amplitude modulating waves, means for amplitude detecting said harmonically related waves after separation, and means for processing said amplitude detected waves to derive said modulating waves.
